(57) **CLAIM**

The ornamental design for a clubface as shown and described.

DESCRIPTION

FIG. 1 is a perspective view of a clubface showing my/our design.

FIG. 2 is a front elevation view thereof.

FIG. 3 is a rear elevation view thereof.

FIG. 4 is a first side elevation view thereof.

FIG. 5 is a second side elevation view thereof.

FIG. 6 is a top plan view thereof; and,

FIG. 7 is a bottom plan view thereof.

The evenly spaced broken lines shown on the drawing views form no part of the claimed design. The dash-dot-dash broken lines represent the boundary lines and form no part of the claimed design.

1 Claim, 7 Drawing Sheets(56)
